UNITED STATES PATENT OFFICE.

JOSEPH F. MOODY, OF RANGER, TEXAS.

GRIPPING DEVICE.

Application filed April 17, 1922. Serial No. 553,877.

To all whom it may concern:

Be it known that I, JOSEPH F. MOODY, a citizen of the United States, residing at Ranger, in the county of Eastland and State 5 of Texas, have invented new and useful Improvements in Gripping Devices, of which the following is a specification.

This invention relates to appliances employed in connection with oil well apparatus 10 for gripping the tubing sections, and its object is to provide an appliance of this kind embodying certain novel improved details of construction and modes of operation to be described hereinafter, this application being 15 a continuation in part of my application Serial Number 346,363 filed December 20, 1919.

In order that the invention may be better understood, reference is had to the accompanying drawings, wherein:

Figure 1 is a central vertical section of the device; Fig. 2 is a plan view thereof; Fig. 3 is a vertical section showing a modified base member; Fig. 4 is an elevation of a 25 latch; Fig. 5 is a vertical section showing the base member used as a tubing ring, and Fig. 6 is a horizontal section on the line 6—6 of Fig. 5.

Referring specifically to the drawings, 30 denotes the upper end of a well casing supporting a casing head 11 of ordinary construction, and the latter supporting the base of the gripping apparatus which is the subject matter of the present application for patent.

The gripping elements of the apparatus 35 consist of wedge-shaped jaw members 12 commonly termed "slips" in the art. These slips are arranged in a circular series to surround the string of well-tubing 13 to be elevated or lowered in the casing 10. The slips 12 are positioned at the top of a member 14, having a vertical socket or opening 15 which is tapered downwardly so that when the slips move downwardly in said opening they are crowded inwardly to grip the tubing 13 or other work, whereas when they are elevated they recede and release the tubing. Near the top, the opening 15 is enlarged so that the slips may recede far 45 enough to clear the collar 13^a on the tubing, without the slips being elevated so far as to leave the opening 15, their lower ends remaining in the opening at the limit of their upward movement. The slips are therefore 50 always in proper position for coming into gripping engagement with the work.

The slips 12 are suspended by chains or other suitable connections 16 from a supporting member 17 having the form of a ring so that the work may pass therethrough. This ring is positioned above the socket member 14 and it is yieldably supported so that it may descend in the direction of said member in order to lower the slips 12 to gripping position. The chains 16 60 are so positioned that the slips 12 have a normal tendency, when being elevated, to swing outwardly into the enlarged top portion of the opening 15.

The socket member 14 has diametrically 70 opposite outstanding side ears 18 which slidably support vertically positioned stems 19 supporting at their upper ends the ring 17, said ring having diametrically opposite outstanding ears 20 to which the stems are 75 secured by bolts or other suitable fastening means. The ring 17 is held normally elevated above the member 14 by a helical spring 21 encircling at the lower end of said member and seating on the ears 18, and bearing 80 at its upper end against the bottom of the ring ears 20. The slips 12 are located inside the spring 21 and the upper convolution of the spring fits snugly around the series of chains 16. The upward movement of the 85 ring 17 is limited by washers 22 mounted on the stems 19 and held by cross pins 23, these washers being located beneath the ears 18 to engage the same when the ring is at the desired limit of its upward movement. By 90 providing the stems 19 with a plurality of vertically spaced holes for the pins 23, the position of the stop abutments formed by the washer 22 may be changed to locate the normal position of ring 17 closer to the 95 member 14, and thus bring the slips 12 nearer their gripping position.

A means is also provided for locking the ring 17 after it has gone down to allow the slips 12 to grip the work, such locking 100 means being associated with both ring-supporting stems 19. Each stem has a keeper notch 24 for a spring pressed latch 25 mounted in a housing 26 on the ear 18 through which the stem passes. The latch 105 25 has a projecting side pin 27 protruding through a slot 28 in the housing 26, so that the latch may be retracted and held in inoperative position. The slot 28 has a side recess 28^a for locking the latch 25 in retracted 110 position, this being done by swinging the pin 27 over into the recess, the latch of course

being free to turn in the housing 26 to permit this movement of the pin. To the upper end of the stem 19 is connected a chain 29 supporting a sleeve 30 which is loosely mounted on the stem. When the stem 19 has gone down and is being locked by the latch 25, the sleeve 30 is directly above the latch, so that when the latter is retracted the sleeve slides down on the stem to seat over the keeper notch 24 and thus prevent the latch, when it is released, from again entering said notch. When the stem 19 rises, the sleeve 30 remains in front of the latch 25 until the slack is taken out of the chain 29, whereupon said chain draws the sleeve upwardly on the stem clear of the latch, so that the latter may again advance to engage the notched side of the stem, ready to slip into the keeper notch when the stem again goes down. A latch mechanism as hereinbefore described is provided for each stem 19, and its purpose will be more fully described hereinafter.

With the ring 17 is also associated a pair of oppositely positioned work-gripping members, the same being pivoted to the ears 20, and each consisting of a serrated jaw 31 having rearwardly extending and laterally spaced shanks 32 extending into a recess 20^a in the ear 20, with a pivot pin 33, carried by said ear, extending through the shanks. Each gripping member is supported in this manner, one ear 20 supporting one of said members, and the other ear supporting the other member. The gripping members are pivoted to swing in a vertical direction, and they come to gripping position when they swing forwardly and toward each other. It will also be noted that the gripping members in operative position are located above the ring 17, and their downward swing to gripping position is limited by said ring, the top of the latter having grooves 34 adapted to receive the shanks 32. The pivot pins 33 are stationary and around the same are coiled springs 35 having a connection with the shanks 32 for giving the gripping members a normal tendency to swing forward to gripping position. A means is also provided for locking the gripping members in inoperative position, said means being latches 36 carried by the ears 20 and adapted to catch over lips 37 on the back of the jaws 31 when the gripping members are swung back into the recesses 20^a. To the latches 36 are connected lines 36^a to enable the same to be tripped from a distance.

To the bottom of the slips 12 are connected chains 38 which extend downwardly through the opening or socket 15, and are fastened at their lower ends to ears 39 on the bottom of the member 14. The chains also serve to maintain the circular arrangement of the series of slips.

65 The casing head 11 carries a base mem-

ber 40 supporting the socket member 14 and constructed to serve as a tubing-guide also. The base 40 has a vertical opening 41, and near the top it has an internal shoulder 42 on which the member 14 seats, the diameter of 70 the latter being such that it may enter the opening 41. Set screws 43 passing through the side of the base, and entering an encircling groove 44 in the exterior surface of that portion of the socket member which 75 seats in the opening 41, securely fastening said member to the base. The bottom of the base 40 seats in a socket 45 in the top of the casing head 11, and it is securely held in said socket by set screws 46 carried by the 80 casing head and entering an encircling external groove 47 in that portion of the base which seats in the casing head socket.

At the bottom of the base 40, the opening 41 is reduced in diameter, this reduced lower portion of opening being denoted by the reference character 48. The bottom of the base is formed with a short depending cylindrical extension 49 through which the opening 48 is contained. The opening 48 produces a shoulder 50 in the base, and this shoulder has an annular upstanding rib 51 surrounding the top of the opening 48. It will be noted that the opening 48 is not concentric with the opening 41 but is offset somewhat to one side of the center of the base, and the extension 49 is similarly arranged, which is for a purpose to be presently described. To that side of the extension 49 which is farthest from the center of the base is fastened a depending resilient shank 52 carrying at its lower end a presser shoe 53 the purpose of which will be hereinafter stated.

Fig. 1 shows the appliance set when a string of tubing 13 is to be lowered into the well. The slips 12 are in elevated position and retracted so as to allow the tubing and the collar 13^a to freely pass. In the event of an accident to the hoisting apparatus causing the string to drop, a pull on the lines 36^a will operate the latches 36 to release the grippers 31 so that they swing over into engagement with the string. This couples the string to the ring 17 and hence the latter descends and the slips 12 go down into the opening 15 to grip the string and thus stop the descent thereof. The grippers 31 can also be made to operate automatically by attaching the latch-tripping lines 36^a to the governor mechanism disclosed in my Patent 110 No. 1,422,289 granted July 11, 1922. It might be stated that this governor mechanism embodies a rotatable shaft which is driven by means of rollers having a normal frictional engagement with the descending 115 line of pipe. This shaft has a driving connection with a second shaft having a governor of usual construction thereon clutch means being employed therewith for driving a line carrying shaft for winding a line 120 125 130

thereon upon rotation of said governor beyond a predetermined speed. Since the governor mechanism is a part of the prior art and no novelty is claimed for such mechanism, per se, it has not been illustrated. The ring 17 also goes down to set the slips 12 in gripping position when the elevator E which supports the string reaches said ring, whereupon it bears down on the ring, and as the elevator continues to descend the slips 12 go down into the opening 15 as before to grip the string. The slips 12 are maintained in gripping position by the latches 25, so that the elevator may now be removed for attachment to the next string of well tubing after the same has been coupled to the string which had just been run in. The latches operate as a safety device if the operator should be careless in allowing the elevator to catch again on the collar 13^a and allow the string to rise sufficiently to let the strips 12 rise out of the opening 15 and release the string. After the next string has been coupled as described, and the elevator has been replaced, the lowering operation may be resumed. However, before this can be done, the slips 12 must be elevated to release the string, this being done by retracting the latches 25, whereupon the spring 21 which was compressed when the ring 17 went down, forces the ring upwardly to pull the slips clear of the string. When the latches 25 are retracted as stated, the sleeves 30 slide down in front thereof to prevent the same from again entering the notches 24, and when the stems 19 go up as the ring is pushed up by the spring 21, the chains 29 draw the sleeves 30 upwardly clear of the latches as hereinbefore described so that they may again advance into contact with the stems, ready to slip into the notches when the stems again go down. As the grippers 31 are normally free of the string when it is being run in or lowered, the serrated jaws do not soon dull so as to allow the string to slip when they swing into gripping engagement therewith.

When elevating or lowering a string of well tubing it is usually run through a tubing ring which is set on the casing head in the same manner as the base member 40. The way in which the hoisting line is attached to the string always causes the latter to hang to one side and not exactly in the center of the ring. With the string in this position, the slips 12 will not set perfectly when going down to gripping position, and the slips on the side of the string which is farthest from the center of the tubing ring are also apt to catch on the collar 13^a. This difficulty is entirely done away with by the off-center location of the opening 48. The base 40 will be turned to such a position that the side of the opening 48 which is nearest the center of the base faces in the

direction the string tends to lean or deviate from a central position, and hence it bears against this side of the opening as shown in Fig. 1, and is so held by the lateral pressure of the shoe 53. The opening 48 is so dimensioned and located that when the string is in the position described it is exactly centered in the base 40, and hence it is also centered with respect to the circle of slips 12. The shoe 53 being carried by a resilient shank 52 is free to yield to allow the collars 13^a to pass.

When elevating a string of tubing 13 out of the well, the grippers 31 will be released as to be in engagement with the tubing and hence if the string should start to slip downwardly the ring 17 will go down as before to set the slips 12 in gripping position. However, the grippers 31 do not interfere with the free passage of the tubing sections 13 or the collars 13^a.

The base member 40 may also be left on the casing head 11 to serve as a tubing ring, for holding the tubing 13 off the bottom of the well when the latter is being pumped. The tubing 13 is then gripped by slips 54 wedged in between the tubing and the wall of the opening 48, the top portion of the latter being tapered for this purpose. Figs. 5 and 6 illustrate this arrangement. A packing will be provided to close up the space between the ends of adjacent slips. This packing may be a strip 55 of rubber fitted to one end of each slip 54 and secured thereto by screws 56, the heads of the screws being countersunk, and the back of the strip having lugs 57 which seat in recesses in the edge of the slips. The strips 55 will be thick enough to fill the spaces between the slips, and as the slips fit snugly in the space between the tubing 13 and the wall of the opening 48, and their serrated surfaces bite into the tubing, a perfect seal is obtained.

Fig. 3 shows a modification in the structure of the base member 40. Here, the eccentrically located opening 48 is formed by a bushing 58 seating in an aperture 59 in the bottom of the base member and secured by a cap screw 60. The bushing 58 can be removed when worn and replaced by a new bushing. It will also be noted that the aperture 59 has a downward taper, so that upon removal of the bushing 58, the member 40 can be used as a tubing ring, the slips 54 for gripping the tubing as hereinbefore described being seated in the aperture.

I claim:

1. A gripping device comprising a member having a downwardly tapered vertical opening, a series of slips positioned to descend in said opening to assume a work-gripping position, a vertically movable support for the slips carried by the aforesaid member, means for yieldably holding the support elevated to position the slips in non-

- gripping position, and means associated with the support for coupling the same to the work upon a downward movement of the latter relative to the support.
5. A gripping device comprising a member having a downwardly tapered vertical opening, a series of slips positioned to descend in said opening to assume a work-gripping position, a vertically movable support for the slips carried by the aforesaid member, means for yieldably holding the support elevated to position the slips in non-gripping position, and automatically operating means associated with the support for 10 coupling the same to the work upon a downward movement of the latter relative to the support.
6. A gripping device comprising a member having a downwardly tapered vertical opening, a series of slips positioned to descend in said opening to assume a work-gripping position, a vertically movable support for the slips carried by the aforesaid member, means for yieldably holding the support 15 elevated to position the slips in non-gripping position, and gripper members carried by the support and yieldably engageable with the work to permit upward travel thereof, said members gripping the work to couple 20 the same to the support upon a downward movement of the work relative to the support.
7. A gripping device comprising a base having a work-receiving opening located off the center thereof, a socket member carried by the base, and a series of slips associated with the socket member for gripping the work.
8. A gripping device comprising a base 70 having a work-receiving opening located off the center thereof, a socket member carried by the base, a series of slips associated with the socket member for gripping the work, and means engageable with the work for urging the same in the direction of the wall of the aforesaid opening which is nearest the center of the base.
9. A gripping device comprising a base 80 having a work-receiving opening located off the center thereof, a socket member carried by the base, a series of slips associated with the socket member for gripping the work, and yieldable means engageable with the work for urging the same in the direction of the wall of the aforesaid opening which is nearest the center of the base.
10. A gripping device comprising a base 85 having a work receiving opening, a socket member carried by the base, and a circular series of slips associated with the socket member for gripping the work, the opening of the base being located off the center of the socket member and the circle of slips.
11. A gripping device comprising a base 90 having a work receiving opening, a socket member carried by the base, and a circular series of slips associated with the socket member for gripping the work, the opening of the base being located off the center of the socket member and the circle of slips, the work being engageable with the side of the opening nearest the center of the base, and in which position it is centered with respect 95 to the socket member and the slips.
12. A gripping device comprising a base 100 having an opening, a socket member carried by the base, a circular series of slips associated with the socket member for gripping the work, the opening of the base being located off the center of the socket member and the circle of slips, and means for holding the work against that side of the opening which is nearest the center of the base, in which position the work is centered 105 with respect to the socket member and the slips.
13. A gripping device comprising a base 110 having a work receiving opening, a socket member carried by the base, a circular series of slips associated with the socket member for gripping the work, the opening of the base being located off the center of the socket member and the circle of slips, and means for holding the work against that side of the opening which is nearest the center of the base, in which position the work is centered 115 with respect to the socket member and the slips.
14. A gripping device comprising a base 120 having an opening, a socket member carried by the base, a circular series of slips associated with the socket member for gripping the work, and a bushing mounted in the base opening, the interior of the bushing being located off the center of the socket member and the circle of slips.
- In testimony whereof I affix my signature.
- JOSEPH F. MOODY.
